UNITED STATES PATENT OFFICE.

FRANK GARDINER HIBBARD, OF WAUWATOSA, WISCONSIN.

SPRING-SWITCH.

1,251,024.

Specification of Letters Patent. Patented Dec. 25, 1917.

Application filed June 9, 1917. Serial No. 173,722.

To all whom it may concern:

Be it known that I, FRANK GARDINER HIBBARD, a citizen of the United States, residing at Wauwatosa, in the county of Milwaukee and State of Wisconsin, have invented certain new and useful Improvements in Spring-Switches, of which the following is a specification, reference being had to the accompanying drawing, forming a part 10 thereof.

This invention relates to that class of spring switches commonly known as "universal spring boxes" and "antikickers".

Its main objects are to provide switch mechanism which can be readily adjusted or set so that the switch tongue when thrown from either of its extreme positions past its central position will be carried to and yieldingly held in the other extreme position, or 15 will be automatically returned to and yieldingly held in its initial position, right or left, and which will yield from either extreme position to permit the passage of car wheels from the heel toward the point of the 20 tongue and at the same time will prevent accidental displacement of the tongue; to avoid material variation in the tension or 25 compression of the spring in the operation of the switch whether it be set to shift the tongue from one extreme position to the other or to return it to its initial position; and generally to simplify and improve the 30 construction and operation of switches of this class.

It consists in the construction, arrangement and combination of parts as herein-after particularly described and pointed out in the claims.

In the accompanying drawing like characters designate the same parts in the several figures.

Figure 1 is a plan view of a portion of a switch and of a switch box attached thereto and containing mechanism embodying the 45 invention, the cover of the box being removed and the mechanism set or adjusted for throwing the switch tongue from one extreme position to the other; Fig. 2 is a vertical transverse section on the line 2—2, Fig. 50 1; Fig. 3 is a vertical section substantially parallel with the switch on the line 3—3, Fig. 1; Fig. 4 is a plan view similar to Fig. 1, showing the switch mechanism set or adjusted for left hand throw of the switch 55 tongue; and Fig. 5 is a like or similar view showing the switch mechanism set or adjust-

ed for right hand throw of the switch tongue.

In both Figs. 4 and 5 the switch tongue is shown deflected to the extreme limit from 60 its normal position.

The terms "right" and "left" as used herein refer to the switch as viewed toward the point of the tongue.

In the drawing, a portion of a right hand 65 switch of common construction, comprising a tread 1, a guard 2 and an intermediate tongue 3, is shown.

The switch mechanism constituting the present invention comprises a substantially 70 quadrangular box or case 4, which may be attached to either side of the switch. In the present case it is shown as fastened to the guard side by bolts 5. The box 4 is formed as shown in Figs. 1, 2 and 3, on one of its 75 sides disposed transversely to the switch, with inwardly projecting ears 6 between which a lever 7 is fulcrumed between its ends on a pin 8. On the opposite side, the box is formed with inwardly projecting ledges or 80 flanges 9, which are formed with vertical pin holes 10, 11 and 12.

A toggle comprising two members, a rocker 13 and a link 14, and disposed within the box 4 approximately parallel with the 85 switch, is adjustably connected by a rod 15 and a lug 16 on the under side of the switch tongue 3, as shown in Fig. 2. The rod 15, which passes through an opening in the side of the box 4 next to the switch, 90 is pivotally connected with the toggle link 14 between its ends by a pin 17. The link 14 is pivotally connected at one end with one arm of the lever 7 by a pin 18 and at the other end with the rocker 13 by a pin 95 19. The rocker 13, which is preferably of substantially triangular shape as shown, is formed on the side opposite the pivot pin 19 with three semi-cylindrical notches or pin seats 20, 21 and 22, spaced equidistant 100 from one another transversely to the length of the toggle and to correspond with the spacing of the pin holes 10, 11 and 12. These notches or pin seats, forming pivot bearings, are adapted to engage with and turn on pivot pins 23 and 24, inserted in the holes 10, 11 and 12, according to the adjustment or setting of the mechanism, as hereinafter explained. The pin 23, with which the middle notch or seat 21 of the 105 rocker co-operates, is inserted and remains in the hole 11 for all adjustments of the 110

mechanism. The pin 24, shown in Figs. 4 and 5, is inserted in one or the other of the holes 10 and 12 for right or left hand throw of the switch tongue 3 when it is desired to automatically return the tongue to its initial position after deflection by passing car wheels either to the right or to the left, but it is removed from both holes, as shown in Fig. 1, when it is desired to shift the tongue from one extreme position to the other and yieldingly retain it in its shifted position, as in the operation of a socalled "antikicker."

The end of the lever 7 opposite the pivot pin 18 is connected by a pin 25 with an eye-bolt or rod 26, which is guided at its other end as shown in Fig. 5, in a socket in the opposite wall of the box 4, parallel with the side of the box opposite the switch. A helical spring 27, surrounding the rod 26 and held under compression between a nut 28 threaded on the rod and the opposite wall of the box 4, yieldingly forces the pivot connection between the lever 7 and toggle link 14 toward the pivot pin 23, thereby tending to bend the toggle and shift the switch rod 15 lengthwise. The nut 28, forming an adjustable seat or shoulder for the spring 27, is secured in adjusted position by a lock nut 29, and serves to vary the tension of the spring as may be desired.

The box 4 is provided as shown in Figs. 2 and 3, with a removable cover 30.

When the device is set or adjusted as shown in Fig. 1, to operate as an antikicker, the pivot bolt 24 being entirely removed and the switch tongue 3 is thrown by passing car wheels or by a switch hook from either of its extreme positions past a central position, the pivot pin 19 of the toggle is carried beyond a straight line passing through the centers of the pivot pins 18 and 23 and the spring 27 which has been compressed by the initial movement of the switch tongue reacts through the lever 7, toggle 13—14 and rod 15, to complete the throw of the tongue in the same direction and to yieldingly hold it at the extreme limit of its movement opposite its initial position. For example, when the tongue is forced by a car wheel, switch hook or other means from the position in which it is shown in Fig. 1, against the tread 1 of the switch, past its central position, it will be carried completely over to and yieldingly held against the guard 2.

When the pin 24 is inserted in the hole 12, as shown in Fig. 4, for left hand throw of the switch tongue, and the tongue is deflected by a passing car wheel or otherwise to the left, as shown, the toggle rocker 13 will first turn around its middle seat 21 on the pin 23, till the seat 22 is brought into engagement with the pin 24, whereupon the rocker will be moved away from the pin

23 and will bear solely on the pin 24, thereby shifting the knuckle angle of the toggle before the pivot pin 19 crosses a straight line passing through the pins 18 and 23, and but slightly augmenting the tension or compression of the spring 27 over what it would be if the pin 24 were removed. As soon as the switch tongue is released it will be instantly returned to its initial position against the tread 1 by the reaction of the spring 27, and yieldingly held in that position.

When the pin 24 is inserted in the hole 10, as shown in Fig. 5, for right hand throw of the switch tongue 2, and the tongue is deflected by a passing car wheel or otherwise to the right, as shown, the toggle rocker 13 will first turn around its middle seat 21 on the pin 23 as before, till the seat 22 is brought into engagement with the pin 24, whereupon the rocker will be moved away from the pin 23 and will bear solely on the pin 24, thereby shifting the knuckle angle of the toggle before the pivot pin 19 in its movement toward the switch crosses a straight line passing through the pins 18 and 23. As soon as the switch tongue is released it will be returned to its initial position against the guard, and yieldingly held in that position.

In Figs. 4 and 5 the switch tongue 2 is shown as shifted to a greater extent from its normal position than it ordinarily would be by the flanges of passing car wheels. The holes 10, 11 and 12 in the flanges 9 of the spring box, and the pin seats 20, 21 and 22 in the toggle rocker 13, may be so disposed that when the device is set or adjusted as shown in Fig. 4 or 5, the seat 20 or 22 will be very close to or in actual contact with the pin 24 when the switch tongue is in its normal position, and the rocker will begin to turn on the pin 24 as soon as or nearly as soon as the tongue begins to move from its initial position.

Various changes in the details of construction and arrangement of parts may be made without materially affecting the operation of the mechanism and without departure from the principle of the invention as defined in the following claims.

I claim:

1. In a spring switch the combination with a switch rod, of a lever having a fulcrum between its ends, a compression spring disposed transversely to the switch rod between a fixed abutment and one arm of said lever, and a toggle connected with the switch rod and comprising two pivotally connected members, one of which is pivotally connected with the other arm of said lever and the other has transversely spaced pivot bearings.

2. In a spring switch the combination with a switch rod, of a toggle connected with the switch rod and comprising pivotally con-

nected members, one of which has transversely spaced pivot bearings, while the other has a yielding pivot connection tending to bend the toggle.

5. 3. In a spring switch the combination with a switch rod, of a toggle connected with said rod and comprising two pivotally connected members one of which has three transversely spaced pivot bearings, and the other has a 10 yielding pivot connection tending to bend the toggle.

4. In a spring switch the combination with a switch rod, of a box having adjacent to one side thereof a pivot pin and two pin 15 holes on opposite sides of said pin, a removable pivot pin for either of said holes, and a toggle connected with the switch rod and comprising two members, one of which has three pin seats spaced to correspond with 20 the two pin holes and the pin between them and adapted to rock on the first pin and on the other pin inserted in either of said holes, the other member having a yielding pivot connection on the opposite side of the box 25 tending to force it toward said pins and to bend the toggle lengthwise of the switch rod.

5. In a spring switch the combination of a box having adjacent to one side a pivot pin 30 and two pin holes on opposite sides of said pin; a lever fulcrumed between its ends ad-

jacent to the other side of the box; a removable pivot pin for either of said holes; a toggle consisting of a rocker having three pin seats spaced to correspond and engage 35 with the first pin and with the other pin inserted in either of said holes, and a link connecting the rocker with one arm of said lever; a switch rod connected with the toggle and passing transversely thereto through 40 one side of the box; a rod pivotally connected at one end with the other arm of said lever transversely thereto and guided at the other end in the box, and a helical compression spring surrounding said rod and bearing at one end against a shoulder thereon and at the other end against the box. 45

6. In a spring switch the combination with a switch rod, of a lever having a fixed fulcrum between its ends, a compression spring 50 disposed transversely to the switch rod between a fixed abutment and one arm of said lever, and a toggle connected with the switch rod and comprising two pivotally connected members, one of which is pivotally connected with the other arm of said lever, and the other has shiftable pivot connections with a fixed support. 55

In witness whereof I hereto affix my signature.

FRANK GARDINER HIBBARD.
